CASH REGISTER

Isao Kitai, Nara, Japan, assignor to Sharp Kabushiki
Kaisha, Osaka, Japan

Filed Apr. 16, 1970, Ser. No. 22,458

Claims priority, application Japan Dec. 5, 1969

Term of patent 14 years

Int. Cl. D20—99

U.S. Cl. D52—4

FIG. 1 is a front perspective view of a cash register showing my new design;

FIG. 2 is a top plan view thereof;

FIG. 3 is a bottom view;

FIG. 4 is a front elevational view;

FIG. 5 is a left side elevational view;

FIG. 6 is a right side elevational view;

FIG. 7 is a rear elevational view; and

FIG. 8 is a sectional view thereof.

I claim:

The ornamental design for a cash register, as shown.
